UNITED STATES PATENT OFFICE.

GUSTAF R. SAHLSTROM, OF ROCKFORD, ILLINOIS.

IMPLEMENT FOR HANDLING AND WORKING CONCRETE.

Application filed April 18, 1927. Serial No. 184,517.

This invention relates in general to hand tools and has for its object to provide an improved implement for handling and working materials such as concrete and the like.

- 5 This is a combined tool that serves the purpose of a scoop or shovel for carrying concrete and other materials as, for example, from a mixing box or pile to a bed in which the concrete is to be laid, and it also serves 10 for leveling the top of the concrete and for smoothing it. The tool is characterized by a flat bottom scoop which has a scraping blade at its heel end and a handle by means of which the scoop may be used for lifting and 15 carrying materials and also used for working the tool back and forth on a bed of concrete for leveling and smoothing the top.

I have also aimed to provide as a new article of manufacture a hand implement 20 which combines the functions of several implements heretofore required for the same work and which is so constructed as to enable production at a comparatively low cost.

Referring to the drawing—

- 25 Figure 1 is a perspective view of an implement embodying my invention;

Fig. 2 is a fragmentary perspective view showing more clearly the corner construction and the handle bracket; and

- 30 Fig. 3 is a longitudinal section through the implement showing it in position on a concrete bed.

Referring more particularly to the drawing the implement comprises a shovel or 35 scoop 4 having a broad, flat bottom 5, preferably quadrilateral in shape, a scraping blade 6 at the heel end of the scoop, and a handle 7 properly attached so that it may be used for the purposes intended. These 40 parts may be of any suitable material and shape not inconsistent with the purpose of the invention, although in the preferred embodiment the scoop and blade are of a heavy gauge sheet metal. In the example 45 shown the marginal edges 8 of the scoop are turned up for reenforcing and suitable corner braces 9 are welded or otherwise secured to the upturned sides 8 and to the blade 6 for maintaining these in rigid relative relation. In this instance the blade 6 is integral with the scoop and is shaped to provide a straight scraping edge 10 coincident with the heel end of the scoop. The scraping 50 blade is preferably concave on its face, as shown, for most effectively performing

the scraping and leveling function. The handle 7 may be attached to the scoop or to the blade thereof in any suitable or preferred manner and, as shown, it is secured in a socket part 11 having a flange 12 which fits 60 against the blade and is suitably fixed thereto.

The implement is designed primarily for leveling and smoothing the top of a concrete bed and for laying or handling the concrete 65 required. Its use as a scoop for lifting and carrying material such as sand, gravel, or concrete will be obvious. After the concrete is laid in the bed the implement is used for distributing and spreading. For 70 this purpose the implement is drawn toward the operator and the blade 6 may be dug into the material as deep as necessary. In the work of leveling the scraping edge 10 removes the material from the high spots and 75 carries it along for filling in the hollows. After the concrete has been distributed and leveled the implement is worked back and forth over the top, its broad, flat bottom serving to form a flat level surface and to 80 give the smooth effect desired for a concrete floor, sidewalk, road bed, or the like. The implement is not, however, limited to use with concrete but is well adapted for laying, leveling and smoothing a bed of sand or any 85 other loose material. The implement is also a labor saving factor since it serves the purpose of two or more hand tools heretofore commonly used for the same work.

90 I claim:

1. An implement for handling and working loose materials such as concrete comprising a scoop having a broad flat bottom and a scraping blade at its heel end, and a handle for manipulating the implement 95 either as a scoop or for leveling and smoothing the top of a bed.

2. An implement for handling and working loose materials such as concrete comprising a flat bottom scoop having a scraping blade the scraping edge of which is coincident with the heel end of the scoop, and a handle attached to the heel portion of the scoop whereby it may be manipulated for lifting materials and for leveling and 105 smoothing the top of a bed.

In witness of the foregoing I affix my signature.

GUSTAF R. SAHLSTROM.
